CLAIM

The ornamental design for a clothing care machine, as shown and described.

DESCRIPTION

FIG. 1 is a front perspective view of a clothing care machine, showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the delineated portion 8 in FIG. 1;

FIG. 9 is an enlarged view of the delineated portion 9 in FIG. 1;

FIG. 10 is an enlarged view of the delineated portion 10 in FIG. 2;

FIG. 11 is an enlarged view of the delineated portion 11 in FIG. 2;

FIG. 12 is an enlarged view of the delineated portion 12 in FIG. 5;

FIG. 13 is an enlarged view of the delineated portion 13 in FIG. 5;

FIG. 14 is an enlarged view of the delineated portion 14 in FIG. 6;

FIG. 15 is an enlarged view of the delineated portion 15 in FIG. 7;

FIG. 16 is a front perspective view of the clothing care machine showing the inside thereof by partially excising a portion of right side and front view;

(Continued)

FIG. 17 is an enlarged view of the delineated portion 17 in FIG. 16;

FIG. 18 is an enlarged view of the delineated portion 18 in FIG. 16; and,

FIG. 19 is an enlarged view of the delineated portion 19 in FIG. 16.

The even-dash broken lines illustrating portions of the clothing care machine form no part of the claimed design. The dot-dash broken lines delineating portions of the claimed design that are illustrated in enlargements form no part of the claimed design.

The wall of the right side and portion of the front sections of the clothing care machine have been removed in FIG. 16 for convenience of illustration.
